UNITED STATES PATENT OFFICE

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS

RAILWAY-CAR-DOOR CONSTRUCTION

Original application filed May 18, 1925, Serial No. 31,144. Divided and this application filed March 5, 1928. Serial No. 259,265.

My invention relates to improvements in railway car door construction and particularly to a novel method of forming wall elements of railway car doors.

5 An object of the invention is to construct the wall elements of railway car doors in such a manner that portions thereof will be rigidified at the point of greatest strain by meaningless corrugations of great strength and 10 other portions of the said wall elements where the strain is not so great will be rigidified by the incorporation of embossments defining descriptive characters, indicia, symbols or 15 designating markings whereby the car may be readily identified and an advertising value derived from the use of such embossments.

Other objects of the invention will more clearly appear from the description herein-after following.

20 In the drawings forming a part of this specification, Fig. 1 is a side elevational view of the side door of a railway box car embodying by improved car construction. Fig. 2 is a sectional view taken on a line corresponding 25 substantially to line 2—2 of Fig. 1. Fig. 3 is an enlarged fragmentary horizontal section on line 3—3 of Fig. 1.

Referring to the construction shown in Figs. 1 and 2, I have shown my improvements 30 as applied to the side door of a car, the framework of the door being indicated by vertical marginal members 110—110, upper horizontal marginal members 111 and lower marginal member 112. The main body of the door includes lower and upper panels as indicated at 35 C and D respectively. Said lower panel C is secured to the vertical margins 110—110 as indicated at 113 and to the lower horizontal margin 112 as indicated at 114. The body of the panel is rigidified by a series of horizontal corrugations 115 embossed in the plate and which extend between the vertical members 110—110. The upper panel D is secured to the respective vertical margins 110 as indicated at 116 and to the lower panel and to the upper horizontal marginal member 111 as indicated at 117 and 118 respectively. Said panel D has embossed therein the descriptive symbol 119 which is formed to resist bending 45 of the plate on various cross-lines.

The embodiment of my invention as illustrated herewith is a typical example of a preferred construction for the vertical wall elements of railway car doors and while I have shown the symbol in the upper portion of the panel, this arrangement may be modified in any suitable manner. The disposition of the corrugations at the lower portion of the panel 55 is a preferred arrangement inasmuch as the tendency to bulge is generally greater at the lower part of the car wall than at the top thereof and the series of horizontally extending corrugations provide for great strength intermediate the vertical margins of a panel and it is also desirable, in order to secure 60 sharpness of definition in the parts of the symbol, that the plates in which said symbol is embossed be as thin as the strain on the car wall will consistently permit. Consequently the use of horizontal corrugations at the lower 65 portion of the panel and the symbol at the upper portion thereof permits the use of a lighter plate for the upper portion of a panel.

70 Although I have shown and described a preferred manner of carrying out my invention, the same is merely illustrative and I contemplate all changes and modifications that come within the scope of the claims appended hereto.

75 This application is a division of my earlier application Serial No. 31,144, filed May 18, 1925, for railway car construction; this divisional application being for a car door per se, shown and described but not claimed specifically in said earlier application.

80 What I claim is:

In a sliding car door, the combination with marginal reinforcing members presenting a framework including spaced vertical members having webs extending substantially at 90 right angles to the main plane of the door and defining the depth of the door, said members having a flange defining substantially the outer plane of the door; of a sheet metal panel disposed substantially in the inner plane of 95 the door, said panel being formed with marginal flanges arranged at right angles to the main part of the panel and secured to the webs of the vertical marginal members thereby co-operating with the webs and outer flanges of 100

the vertical members to form **U**-shaped margins; and a series of embossments formed in the central part of said panel, said embossments extending outward and terminating within the space between said **U**-shaped marginal portions to reinforce the marginal flanges of said panel.

In testimony whereof I affix my signature.
ARGYLE CAMPBELL.
